FIG. 1 is a perspective view of a pet house, showing a first embodiment of the new design;

FIG. 2 is a front elevational view thereof;

FIG. 3 is a right-side elevational view thereof;

FIG. 4 is a left-side elevational view thereof;

FIG. 5 is a rear elevational view thereof;

FIG. 6 is a top plan view thereof;

FIG. 7 is a bottom plan view thereof;

FIG. 8 is a front elevational view of a second embodiment thereof;

FIG. 9 is a rear elevational view of FIG. 8;

FIG. 10 is a right-side elevational view of FIG. 8;

FIG. 11 is a left-side elevational view of FIG. 8;

FIG. 12 is a top plan view of FIG. 8; and,

FIG. 13 is a bottom plan view of FIG. 8.

The broken lines showing a logo and graphics applied to the design and ground stakes in FIG. 1 are included for the purpose of illustrating the invention in use, and form no part of the claimed design.
